UNITED STATES PATENT OFFICE.

HERBERT F. OBERGFELL, OF RIVER FOREST, ILLINOIS, ASSIGNOR TO AUTOMATIC ELECTRIC COMPANY, OF CHICAGO, ILLINOIS, A CORPORATION OF ILLINOIS.

DESIGN FOR A COMBINED SWITCH BOX AND SUPPORT FOR A HAND TELEPHONE.

Application filed October 10, 1925. Serial No. 15,079. Term of patent 14 years.

To whom it may concern:

Be it known that I, HERBERT F. OBERGFELL, a citizen of the United States of America, residing at River Forest, in the county of Cook and State of Illinois, have invented a new, original, and ornamental Design for a Combined Switch Box and Support for a Hand Telephone, of which the following is a specification, reference being had to the accompanying drawings forming a part thereof.

I claim:

The ornamental design for a combined switch box and support for a hand telephone, as shown.

In testimony whereof, I have hereunto set my hand this 6th day of October, 1925.

HERBERT F. OBERGFELL.

CERTIFICATE OF CORRECTION.

Design No. 74,985.

Granted April 24, 1928, to

HERBERT F. OBERGFELL.

It is hereby certified that the assignee in the above numbered patent was erroneously described and specified as Automatic Electric Company, of Chicago, Illinois, a Corporation of Illinois, whereas said assignee should have been described and specified as Automatic Electric Inc., of Chicago, Illinois, a Corporation of Delaware; as shown by the records of assignments in this office; and that the said Letters Patent should be read with this correction therein that the same may conform to the record of the case in the Patent Office.

Signed and sealed this 29th day of May, A. D. 1928.

M. J. Moore,
Acting Commissioner of Patents.
